SPRING HINGE MOUNTING FOR SOUND RECORDING AND REPRODUCING HEADS

Lincoln Thompson, Cheshire, and Robert L. Stone, Orange, Conn., assignors to The Sound-
scriber Corporation, New Haven, Conn., a cor-
poration of Connecticut

Application June 25, 1943, Serial No. 492,246

11 Claims. (Cl. 274—24)

This invention relates to improvements in dictating machines, and more particularly to a novel form of stiff spring hinge mounting for the recording and reproducing heads of such machines.

The present invention is especially designed for use on a dictating machine employing disk records of the type disclosed in Reissue Patent 22,183, issued September 22, 1942, to Lincoln Thompson, on an application filed December 17, 1941, entitled Apparatus for recording sound on thin disks. It also constitutes an improvement over the mechanism disclosed in our prior Patent 2,240,321, issued April 29, 1941, entitled Transcribing machine.

The present application is a continuation in part of our prior application S. N. 388,956, filed April 17, 1941, entitled Stepback mechanism for phonograph transcribers, which matured into Patent No. 2,323,257, dated June 29, 1943.

In recording and reproducing machines, it is desirable that the stylus heads of the recording and reproducing apparatus shall be flexible in a vertical direction but free from lateral play, and it is the main object of the present invention to provide a novel hinge mounting for such heads which will accomplish this purpose.

A further object of the present invention is to provide an improved mechanism of the above nature which will be relatively inexpensive to manufacture, simple in construction, compact, ornamental in appearance and very efficient and durable in use.

With these and other objects in view, there have been illustrated in the accompanying drawings several forms in which the invention may be conveniently embodied in practice.

In the drawings:

Fig. 1 is a perspective view of a dictating machine employing the improved mountings for supporting the recording and reproducing heads on their respective arms.

Fig. 2 is a top plan view, on a larger scale, of the reproducing arm and its associated pickup head showing the improved spring hinge connection therebetween for permitting vertical flexibility without lateral play.

Fig. 3 is a side view, on a still larger scale, of the front portion of same as it appears in operating position resting upon a disk record.

Fig. 4 is a plan view of a modified form of flat leaf spring hinge, also embodying the invention.

Fig. 5 is a similar plan view of another modified form of leaf spring hinge which is provided with a central longitudinal slot to enhance the vertical flexibility thereof.

Fig. 6 is a plan view of still another modified form of spring hinge constructed of interleaved rubber and fabric and also having a longitudinal central slot.

Fig. 7 is a transverse sectional view of the same, taken along the line 7—7 of Fig. 6.

Fig. 8 is a side view, partly in section, of the recording arm and head shown in Fig. 1, illustrating the leaf spring hinge which connects the base of said head to the base of said arm, and also showing the short limiting guard-plate mounted upon the top of said arm for engaging the rear end of the recording head.

Fig. 9 is a side view, partly in section, of a modified form of a pickup head similar to Fig. 3, and showing an elongated guard-plate rigidly secured to the top of the pickup arm and having its unsupported forward end lying slightly above the top of said head.

Fig. 10 is a side view, partly in section, showing the pivotal mounting of the reproducer arm.

One advantage of the use of the improved spring hinge connection of the present invention is that side play between the recording and reproducing arms and their respective heads is almost entirely avoided. This is of the utmost importance in producing accurate recordings on a disk record and also in insuring an accurate and uniform amount of backspacing in a transcriber where a stepback mechanism is employed for playing back portions of the record.

Referring now to the drawings wherein like reference numerals designate like parts throughout the several views, the numeral 10 indicates a rectangular cabinet over which a turntable 11 is adapted to be driven at constant speed by a suitable electric motor (not shown). The turntable 11 is provided with a spindle 12 having a square top which serves to centralize a thin record tablet 13 mounted upon the turntable 11.

Provision is also made of a recording arm 14 which is mounted to rotate on a vertical shaft 14a, said arm being caused to travel at constant angular speed across the record 13 by suitable feed mechanism driven by the motor.

Upon the free end of the recording arm 14, provision is made of a recording head 15, spaced a short distance from said arm 14, and connected thereto by means of a thin resilient leaf spring hinge 16 having vertical flexibility, but being quite stiff horizontally to prevent lateral play.

The recording head 15 is adapted to be held upwardly by means of a pair of short upstanding pins 17 and 18 connected together by an elongated counterbalancing small coil spring 19.

The spring hinge 16 is preferably made rectangular in shape, and is preferably provided with eight apertures 20 (see Fig. 8) to receive a like number of rivets 21 for securing the ends of said spring hinge rigidly to the recording arm 14 and recording head 15.

A reproducing arm 22 is also provided, and, as shown in Figs. 1 to 3, is mounted to swing in a horizontal plane when the machine is level on a vertical shaft 22a (see Fig. 10), which is supported by a U-shaped bearing bracket 23 mounted upon the top of the cabinet 10. As clearly shown in Fig. 1, the reproducing arm 22 is provided with a rearwardly extending upwardly offset arm 24 carrying a cylindrical counterweight 25 at its rear end.

Provision is also made of a light wire tracking spring 26 extending upwardly from the rear of the bracket 23 and extending loosely through a small aperture 27 in the upper portion of the offset arm 24 so as to provide a limited amount of backlash.

The spring 26 serves to compensate for or counteract the lateral component of stylus friction on the record tablet tending to dislocate it. It is loose in the aperture 27 so that the arm 22 may be swung a short distance either side of its central or neutral sector before the spring will engage said arm. When the backlash is taken up, however, the spring 26 will oppose the lateral component of stylus friction with a force increasing approximately in accordance with the increase of the angle between the reproducer arm 22 and the central sector.

The operation of a similar compensating device is fully described in Patent No. 2,316,637 to Lincoln Thompson, issued April 13, 1943.

A pickup head 28 is pivotally connected in spaced relation to the forward end of the reproducing arm 22 by means of a thin rectangular leaf spring hinge 29 similar to the hinge 16 previously described. Provision is also made of a pair of upstanding pins 30 and 31 mounted on the pickup head 28 and reproducing arm 22 respectively, and connected by a counterbalancing wire coil spring 32, similar to the spring 19.

The spring hinge 29 is provided with eight apertures 33 for receiving a like number of rivets 34, by means of which said hinge is connected to the upper portions of the reproducing arm 22 and pickup head 28 (see Figs. 1-2-3).

In the modified form of spring hinge shown in Fig. 4 provision is made of a resilient rectangular plate 35 having two apertures 36 and 37 at one end, a single aperture 38 at the other end, and an intermediate aperture 39 on one side of said plate. This form of hinge is employed when a somewhat less resilient and a stiffer construction is desired.

In the modified form of spring hinge shown in Fig. 5 a resilient rectangular plate 40, similar to the plates 16, 29 and 35, is provided, having two sets of apertures 41 and 42, 43 and 44, at the ends thereof, and having an intermediate aperture 45 on one side. The plate 40 is also provided with a longitudinal central slot 45a to increase the vertical flexibility of said hinge.

In the modified form of the invention shown in Figs. 6 and 7, a vertically flexible hinge plate 46 is employed, which is also rectangular in shape and is provided with four corner apertures 47, 48, 49, 50. The plate 46 is also provided with a central slot 51 to increase the vertical flexibility thereof. The plate 46 is constructed of a combination of three interleaved layers of rubber and

fabric having a central canvas sheet 52, and a pair of overlying and underlying rubber layers 52a and 52b respectively.

Fig. 8 shows how the hinge plate 16 is secured to the bottom member 53 of the recording arm 14 and the bottom member 54 of the recording head 15 respectively. The swinging movement of the head 15 is limited by means of a short guard strip 55 secured by means of rivets 56 and 57 upon the top of the recording arm 14. The free end of the guard strip 55 extends forwardly into the space between the recording arm 14 and the rear surface 57 of the recording head 15, and thus serves to limit the amount of upward swinging of said head, as shown in dotted lines.

In the modified form of the invention shown in Fig. 9 a reproducing arm 58 is illustrated which is provided with a resilient hinge plate 59 connected with a pickup head 60 by means of two pairs of rivets 61 and 62 respectively, and provision is also made on the top of the arm 58 of an elongated resilient guard strip 63 rigidly secured at its rear end to the recording arm 58 by means of a plurality of rivets 64. The forward end 65 of the guard strip 63 is slightly raised above the pickup head 60 and serves to limit the upward flexing of said head as shown in dotted lines in Fig. 9.

While there have been disclosed in this specification several forms in which the invention may be embodied, it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claims.

What is claimed is:

1. In a phonograph, a rigid arm mounted to swing over a flat disk record, a stylus head, and a resilient leaf spring hinge for connecting said arm to said head, said hinge being flexible vertically but not horizontally.

2. In a phonograph, a rigid arm mounted to swing over a sound record, a stylus head, a spring hinge having no lateral flexibility connecting said head with said arm, and means connected to said arm to counterbalance the weight of said head.

3. In a phonograph, a rigid supporting arm mounted to swing upon a vertical axis over a rotating disk record, a stylus-carrying head, and a short thin leaf spring hinge connected rigidly at its ends to said arm and said head respectively to provide a flexible connection therebetween, whereby said head will be permitted to yield freely in a vertical direction but will have substantially no lateral yieldability.

4. In a phonograph, a recording arm mounted to swing upon a vertical axis over a rotating disk record, a stylus-carrying recording head, a short thin resilient leaf spring hinge rigidly connected at its ends to the bottom portions of said recording arm and said recording head respectively, whereby said head will be permitted to yield freely in a vertical direction, but will have no lateral yieldability.

5. In a phonograph, a reproducer arm mounted to swing upon a vertical axis over a rotating disk record, a pickup head, and a thin resilient spring hinge rigidly connected at its ends to the top portions of said reproducing arm and said pickup head respectively, whereby said pickup head will be permitted to yield freely vertically, but will have substantially no lateral yieldability.

6. The invention as defined in claim 3, in which said supporting arm and said stylus-carrying head are each provided with an upstanding pin, and an elongated coil spring connected to said pins to counterbalance the weight of said head.

7. The invention as defined in claim 3, in which said leaf spring hinge comprises a laminated sheet of fabric and rubber.

8. The invention as set forth in claim 3, in which said leaf spring comprises a central sheet of canvas, an overlying sheet of rubber, and an underlying sheet of rubber.

9. In a phonograph, a recording arm mounted to swing upon a vertical axis over a rotating disk record, a recording head, a thin resilient leaf spring hinge rigidly connected to the bottom portions of said recording arm and said recording head respectively, and a short flat guard plate attached to the top of said recording arm for 20 engaging the rear surface of said recording head to limit the upward flexing thereof.

10. In a phonograph, a reproducing arm mounted to swing upon a vertical axis over a rotating disk record, a pickup head, a spring plate hinge rigidly secured at its ends to the upper portions of said reproducing arm and said pickup head respectively, and an elongated guard plate having its rear end rigidly secured on the top surface of said reproducing arm and having its forward end unsupported and raised slightly above the upper surface of the rear portion of said pickup head to limit the upward flexing thereof.

11. The invention as defined in claim 3, in which said leaf spring hinge comprises a thin rectangular sheet of resilient material and is provided with a narrow longitudinal slot therein to enhance the vertical flexibility thereof.

LINCOLN THOMPSON.
